UNITED STATES PATENT OFFICE

2,255,375

GAS PRODUCER

Alfred E. Blake, Caldwell, N. J.

Application April 20, 1940, Serial No. 330,690

3 Claims. (Cl. 48—63)

This invention relates to a gas producer that is suitable for producing gas from different grades of coal in a rapid and economical manner even when cheap grades of coal are used.

This invention is also adapted for the production of producer gas with different sizes of anthracite coal, such as rice or barley.

One of the objects of this invention is to produce gas in a large quantity per unit of grate area in such a manner that fixed charges are kept low and economy of material is effected.

Another object of the invention is to keep down the expenses for water and power for steaming and for scrubbing the gas clean where clean gas is needed.

Other objects and advantages of the invention will be understood from the detailed description.

The invention will be understood from the description in connection with the accompanying drawings, in which:

Fig. 1 is a vertical section partly broken away, showing an illustrative embodiment of the invention;

Fig. 2 is a section along the line 2—2 of Fig. 1 with parts removed;

Fig. 3 is a plan view of Fig. 1 with parts removed;

Fig. 4 is a vertical section on an enlarged scale showing some of the details; and

Fig. 5 is a section along the line 5—5 of Fig. 4.

Reference character 1 indicates a base or foundation upon which one or more producers made in accordance with this invention are mounted. The ground floor is indicated at the level 1'.

The producer shell 2 is made of thick steel side walls and is provided with a thick steel top 3 so that the producer shell will resist considerable pressures. The shell 2 is surrounded with a water jacket 4 leaving a space 5 around the shell. The upper and lower portions of the space 5 are connected by pipes 6 and 6' to a steam drum 7 that is provided with the usual fixtures (not shown) to enable the steam that collects in the drum 7 to be used for any purpose where comparatively low pressure steam is needed. The superheated water under pressure in the jacket 4 makes it possible to keep the shell 2 at substantially higher temperatures than is usual in gas producers, thus reducing the tendency for side wall clinker to form on the inside of the furnace, and also preventing consideration of moisture in the air blast on the inner side of the producer shell below the fire or in the reaction zone, thus avoiding corrosion of metal by acids that takes place if water is per-

mitted to condense in contact therewith. Also, by using the producer jacket as a low pressure boiler, no overflow water is wasted. The heat that would thus be wasted is utilized to form steam, and much less water is needed for the jacket than is needed where water vapor is used merely for endothermic purposes with excess hot water wasted to the sewer. The steam evolved in the drum 7 at working pressure may be used for different purposes, such as purging the coal feed magazine, heating the building, drying coal or heating feed water. It is to be understood that suitable insulation may be used for heated parts wherever desired to avoid loss of heat.

15 The operating floor level is shown at 8. The top of the producer shell is used as a feed water heater by providing a heater 9 and introducing the water thereinto as will be described below.

A hollow spreader 10 for coal having hollow arms is provided and is driven by a motor 11 through the shaft 12 as shown in Fig. 4. The miter gear 13 on the shaft 12 meshes with the miter gear 13' on a rotatable sleeve 14 that carries the spreader 10. A set screw 15 connects the gear 13' to the sleeve 14 and a set screw 15' connects the sleeve 14 to a pipe 19. A support 16 is provided for the gear 13' and has an arm 16' for supporting an end of the shaft 12.

20 A valved water pipe 17 is provided for feeding water into a container 18 at the upper end of a pipe 19 that is slidable in the sleeve 14 and is held in adjusted positions by the set screw 15. Two water inlet tubes 20 extend from the container 18 inside the pipe 19 into the spreader 10, 25 and the ends of these pipes terminate short distances from the ends of the arms of this spreader. A vertically adjustable container 21 is adjustably supported on the top of the producer by threaded rods 21' having nuts thereon. A flexible tube 22 connects the bottom of the container 21 to the water heater 9, and a stuffing box 22' is provided around the pipe 19 for making a water tight connection with the container 21. Water is pumped from feed water heater 9 through outlet pipe 23 by means of pump 23' and forced into the upper portion of the water leg 6'.

25 A stepped grate 24 is provided at the bottom of the producer shell 2. This grate may, for example, be of the sort shown in my application Serial No. 318,794, filed February 14, 1940, or it may be of other types with which the depth of the fire bed can be regulated by the rate at which the ashes are removed.

30 A feed pipe 25 is provided for feeding coal

from the coal supply 26, and this feed pipe is provided with valves 27 to enable measured quantities of coal to be fed to the producer. These valves may be governed in the well known way to feed coal automatically at such a rate that so much coal will not be permitted to remain under the feed pipe as to cause an obstruction to the free egress of gas from the surface of the coal bed. A counting and recording means may also be provided in the well known way, to show the number of times the valves 27 are opened and the amount of coal fed through them. The coal storage bin 26 may supply a plurality of two or more producers, one producer and a portion of another one being indicated in Figs. 1 and 2. The coal is fed by gravity from the bin 26 which receives the coal from the elevator 28.

A take-off or outlet pipe 29 for hot producer gas leads from the producer to the bottom of a gas scrubber 30 that contains particles 31 of solid material such as coke, ceramic material, non-corrosive metal, or the like, supported on a grill 32. Water spray pipes 33 are provided for the scrubber 30.

A heat exchanger 34 surrounds the pipe 29 to heat air for the producer and to cool the gas before it reaches the scrubber 30. A spiral fin 35 may be provided on the pipe 29 inside the heat exchanger 34 to aid in transferring the heat from the pipe 29 to the air in the heater 34. A twisted ribbon 35' may be inserted inside the vertical portion of the pipe 29 to increase the rate of heat transfer from the gas inside the pipe 29 to the air passing through the heat exchanger 34.

An air pipe 36 leads from the lower end of the heater 34 to a blast fan 37 from which an outlet pipe 38 leads to an ash pit 39 below the producer. A distributor 40 is provided at the end of the pipe 38, and a steam connection 41 leads from the drum 7 and terminates in the pipe 38 in the direction in which the air therein passes from the fan 31, so that the steam and air become well mixed before being projected into the ash pit 39.

The ash pit 39 is provided with a sloping bottom 42 having an outlet 43 for ashes at the bottom of the side wall, this outlet being closed by a closure 44 that is provided with a threaded rod 45 having a gear 45' thereon operated by a crank 46 for raising and lowering the closure 44. An elevator 47 is provided for hoisting the ashes.

A gas outlet pipe 50 extends from the scrubber 30 and leads to an involute positive pressure gas pump 51 from which a valved outlet 52 leads to the plant distribution system. An automatic pressure regulator 53 is provided between the pipes 50 and 52 to enable portions of the gas production to be recirculated through the pump 51 in accordance with variations in the demand for gas.

A valved pipe 55 is provided to be used as a purge pipe. The usual explosion head 56 is indicated below the grate 24.

While the producer is operating, the coal is automatically fed thereto at the desired rate in successive charges and the leveling arm 10 quickly levels the upper surface of the coal bed and the water circulating through the leveler 10 not only protects this leveler from the heat but this water becomes heated before it is introduced into the heater 9. The temperature of the feed water in the heater 9 is preferably kept above 195° F. to insure thorough deaeration or removal of oxygen which would be very detrimental to the interior of the jacket 5 due to corrosion by this oxygen.

A suitable outlet is provided in the top of the feed water heater 9 for the escape of the oxygen.

The spreader or coal leveler 10 is made adjustable to different heights so that when smaller sizes of coal or coke are used the spreader arm 10 can be lowered to different positions, because different depths of fuel are used in accordance with the size of the fuel particles so that the resistance to the passage of the gas through the fuel bed does not become excessive. The spreader or leveler 10 keeps the upper surface of the coal bed substantially level, so that thin zones of coal do not occur to permit channeling of air and steam therethrough.

The opening for the air heater 34 is preferably so located that the air therefor is taken from the operating room, and this air is used to pre-cool the hot gas, thus reducing the amount of water needed for cooling and the power necessary for pumping such water. Or, for any given quantity of water used in the scrubber, the moisture content of the washed gas will be lower when the heat exchanger 34 is in use than without it, because the wash water will not become heated as much by cool gas as by hot gas; consequently, the gas coming from the cooler wash water will have a lower moisture content or lower dew point, thus providing improved gas to be used for many purposes where water in the combustion products is objectionable. Furthermore, the lower the temperature of the wash water the greater the amount of impurities it will dissolve from the gas, particularly the objectionable hydrogen sulphide.

Whenever desired, the scrubber 30 can be made in sections or compartments so that fewer numbers of compartments can be used with low rates of generation of gas, so that the supply of water to the unused compartments can be cut off. Since the scrubber is located on the ground floor, the cost of pumping water to an unnecessary height is eliminated, a considerable weight is removed from the operating floor thus reducing installation costs, easy access to the scrubber is provided, and the available floor space on the operating floor 8 is increased while the scrubber itself can be utilized in part for the support of the floor 8. Also, by locating the blast fan 37 on the ground floor, the lengths of the inlet and outlet connections are reduced and the necessity of supporting the weight of the fan on the operating floor is obviated and danger of the fan causing vibration of the operating floor is eliminated. As the ash pit 39 is, in effect, a portion of the ground floor, the expense of a steel bin for ashes is not necessary.

What is claimed is:

1. In a gas generator, a producer shell, a water jacket around said shell, means to maintain pressure in said jacket considerably above atmospheric, a feed water heater at the top of said shell, a pump for forcing water from said heater into said jacket, a steam collecting means, steam take-off means connecting the jacket and the collecting means, and means for introducing steam from the collecting means into the generator, hollow rotatable coal-leveling means in said shell, and connections for introducing cold water into said hollow means and from thence into said feed water heater.

2. In a gas generator, a producer shell, a water jacket around said shell, means to maintain pressure in said jacket considerably above atmospheric, a feed water heater at the top of said shell, a pump for forcing water from said heater into said jacket, a steam collecting means, steam

take-off means connecting the jacket and the collecting means, and means for introducing steam from the collecting means into the generator, hollow rotatable coal-leveling means in said shell, connections for introducing cold water into said hollow means and from thence into said feed water heater, and a heater heated by hot gas from said producer shell for air to be used in said gas generator.

3. In a gas generator, a producer shell, a water jacket around said shell, means to maintain pressure in said jacket considerably above atmos-

pheric, a feed water heater at the top of said shell, a pump for forcing water from said heater into said jacket, a steam collecting means connected to the top of said jacket, hollow rotatable coal-leveling means in said shell, connections for introducing cold water into said hollow means and from thence into said feed water heater, a heater heated by hot gas from said producer shell for air to be used in said gas generator, and means to introduce steam generated in said steam jacket into said gas generator.

ALFRED E. BLAKE.

CERTIFICATE OF CORRECTION.

Patent No. 2,255,375

September 9, 1941.

ALFRED E. BLAKE.

It is hereby certified that error appears in the printed specification of the above numbered patent requiring correction as follows: Page 1, first column, line 52, for the word "consideration" read --condensation--; page 2, second column, line 33, for "hdyrogen" read --hydrogen--; and that the said Letters Patent should be read with this correction therein that the same may conform to the record of the case in the Patent Office.

Signed and sealed this 14th day of October, A. D. 1941.
